ELECTRIC CABLE

Walter T. Peirce, Worcester, Mass., assignor to
 The American Steel and Wire Company of New
 Jersey, a corporation of New Jersey

Application October 26, 1943, Serial No. 507,693

14 Claims. (Cl. 174—13)

This invention relates to an electric cable and more particularly to cables having oil or oil saturated insulation of the type shown in the Thompson Patent No. 2,138,362, and in the Peter-
 son Patent No. 2,316,808.

In this type of cable, the electrical conductors and insulation are enclosed in an oil tight sheath. Due to temperature changes the pressure within the cable will vary if compensating means are not provided. This causes trouble due to ionization and also distortion and breakage of the sheath. Various compensating means have been proposed as shown in the above mentioned patents.

It has been proposed to use capillary tubes but they have certain limitations. It has been found that it is difficult to effect stabilization over long lengths of cable such as one or more miles in length through tubes of capillary size. A single capillary tube cannot contain a large amount of oil and therefore it is necessary to use a plurality of such tubes in order to take care of large temperature or pressure changes.

With the cables now in use there is the possibility that the pressure within the cable will fall below atmospheric. This condition is undesirable and it is an object of this invention to provide an electric cable in which the pressure of the oil will always be above atmospheric.

Another object is to provide a capillary tube having a relatively large cross-sectional area.

A still further object is to provide an electric cable having means for keeping the pressure throughout the length of the cable constant.

These and other objects will be more apparent after referring to the following specification and attached drawing, in which:

Figure 1 is a cross-sectional view of the cable;

Figure 2 is a side view of the cable shown in Figure 1 with certain parts of the cable removed to more clearly disclose its structure; and

Figure 3 is a schematic sketch showing the operation of the system within the cable.

Referring more particularly to the drawing, the reference numeral 2 indicates the metallic conductors of the cable, each of which is surrounded by oil impregnated insulation 4. A metallic tape 6 surrounds the insulation 4 and a metallic and fibrous binder 8 holds the three conductors 2 together and makes contact between the metallic tape 6 and the impervious sheath 10 which surrounds the entire cable. Between the conductors 2 are a plurality of concentric tubes 12 and 14. The space in the interstices between the conductors not occupied by the con-

centric tubes 12 and 14 is filled with fibrous material 16.

In the manufacture of the cables the conductors 2 and the concentric tubes 12 and 14 are twisted together in spiral form. The lay of this spiral, that is, the distance between the bottom loops 18, in ordinary cable is between 40 to 80 inches. These cables are ordinarily made in lengths of 200 to 500 feet and these lengths are joined as shown at 20 in Figure 3. The outer concentric tube 12 is perforated at short intervals, preferably at 1 1/3 times the length of the lay of the cable so that perforations would occur every 50 to 90 inches in the tube. As shown, three concentric tubes are used and in this case the perforations in any one tube may be at three times this distance with the openings occurring in the tubes successively so that there will be an opening every 50 or 90 inches throughout the length of the cable.

20 The concentric tubes 12 and 14 are filled with an inert gas such as nitrogen or helium. As the oil expands, due to the rising temperature of the cable, the resulting pressure forces the oil into the openings 22 in the cable where it collects at the low spots 18 between the tubes. The tubes 12 and 14 are so spaced that the oil is retained therein due to capillary action. By using concentric tubes, a large increase in the surface area in contact with the oil is provided, thus causing

25 the oil to have a greater tendency to form capillary blocks with a larger bore. This provides the space required to take care of the oil and gas expansion and contraction. The trapped oil in the low spots 18 blocks off the gas which is normally 30 in the tube and causes the gas to collect in separate segments at the top of the loops 24. As the oil rises in the space between the concentric tubes, the gas is put under pressure and as the cable cools off the pressure of the gas drives the oil back into the cable through the openings 22 and thus the system operates with a very narrow

35 pressure swing. At one of the joints 20 an oil or a gas reservoir 45 is provided. Within this reservoir is a supply of oil 28 which is fed to the cable by means of tube 30. The oil entering the joint 20 through the tube 30 will replace the oil that flows from the cable through the openings 22 into the oil trap 40 48. The top portion 32 of the reservoir 26 is filled

45 50 of the pressure swings would the pressure within the cable go below atmospheric. This is accomplished as follows:

At one of the joints 20 an oil or a gas reservoir 55 50 is provided. Within this reservoir is a supply of oil 28 which is fed to the cable by means of tube 30. The oil entering the joint 20 through the tube 30 will replace the oil that flows from the cable through the openings 22 into the oil trap 50 58. The top portion 32 of the reservoir 26 is filled

with the inert gas and a stand pipe 34 is connected to the inner and outer tubes 12 and 14 and has its open end in communication with the gas chamber 32 in the reservoir 28. The gas in the reservoir is maintained at a positive pressure preferably between 5 and 15 pounds per square inch. In this way pressure within the tubes 12 and 14 is stabilized at a positive value above atmospheric pressure and this pressure is made effective over long lengths of cable by means of the pressure transmitting qualities of the tubes themselves.

The collecting of the oil in the low sections 18 of the tubes interferes with the transmission of the pressure from the reservoir 28 to distant parts of the cable due to the friction of the oil against the walls of the capillary tubes 12 and 14. It is impossible to transmit this pressure over distances greater than 200 or 300 feet and even in such distances there is a gradual diminution in pressure. To overcome this the inner tube 14 is provided with an opening 36 at predetermined intervals throughout the cable. This inner tube 14 conducts the gas pressure of the reservoir 28 past the oil traps 18 and through the openings 36 transmits the gas pressure of the reservoir to the gas between the inner and outer tubes.

While one embodiment of the invention has been shown and described, it will be apparent that other modifications and adaptations may be made without departing from the scope of the following claims.

I claim:

1. A cable comprising a conductor, insulation about the conductor including an oil, a fluid-tight sheath about the insulation, a tube between the conductor and sheath, a second tube containing gas surrounding and substantially parallel to said first tube, said outer tube having an opening therein for admitting oil thereto, the space between said tubes being such that the oil is retained therein due to capillary action.

2. A cable comprising a conductor, insulation about the conductor including an oil, a fluid-tight sheath about the insulation, a helical tube between the conductor and sheath, a second tube containing gas surrounding and substantially parallel to said first tube, said tubes providing a dome containing trapped gas, said outer tube having an opening therein for admitting oil thereto to provide contact between the trapped gas and the oil, said opening being so positioned that the trapped gas is retained in the dome by the oil.

3. A cable comprising a conductor, insulation about the conductor including an oil, a fluid-tight sheath about the insulation, a tube between the conductor and sheath containing gas, a second tube containing gas surrounding and substantially parallel to said first tube, said outer tube having openings therein for admitting oil thereto, the space between said tubes being such that the oil is retained therein due to capillary action, said inner tube having an opening therein to transfer the pressure of said gas past the oil between said tubes.

4. A cable comprising a conductor, insulation about the conductor including an oil, a fluid-tight sheath about the insulation, a tube between the conductor and sheath containing gas, a tube containing gas surrounding and substantially parallel to said first tube, said tubes providing a dome containing trapped gas, said outer tube having an opening therein for admitting oil thereto to provide contact between the trapped gas and the

oil, said opening being so positioned that the trapped gas is retained in the dome by the oil, said inner tube having an opening therein at said dome to transfer the pressure of said gas past the oil between said tubes.

5. A cable comprising a conductor, insulation about the conductor including an oil, a fluid-tight sheath about the insulation, a tube between the conductor and sheath containing gas, a second tube containing gas surrounding and substantially parallel to said first tube, said outer tube having openings therein for admitting oil thereto, the space between said tubes being such that the oil is retained therein due to capillary action, said inner tube having an opening therein to transfer the pressure of said gas past the oil between said tubes, and a reservoir containing gas under pressure connected to said tubes.

6. A cable comprising a conductor, insulation about the conductor including an oil, a fluid-tight sheath about the insulation, a tube between the conductor and sheath containing gas, a second tube containing gas surrounding and substantially parallel to said first tube, said outer tube having openings therein for admitting oil thereto, the space between said tubes being such that the oil is retained therein due to capillary action, said inner tube having an opening therein to transfer the pressure of said gas past the oil between said tubes, and a reservoir containing gas under pressure connected to said tubes, said reservoir also containing oil connected to the oil in said cable.

7. A cable comprising a conductor, insulation about the conductor including an oil, a fluid-tight sheath about the insulation, a tube between the conductor and sheath containing gas, a tube containing gas surrounding and substantially parallel to said first tube, said tubes providing a dome containing trapped gas, said outer tube having an opening therein for admitting oil thereto to provide contact between the trapped gas and the oil, said opening being so positioned that the trapped gas is retained in the dome by the oil, said inner tube having an opening therein at said dome to transfer the pressure of said gas past the oil between said tubes, and a reservoir containing gas under pressure connected to said tubes.

8. A cable comprising a conductor, insulation about the conductor including an oil, a fluid-tight sheath about the insulation, a tube between the conductor and sheath containing gas, a tube containing gas surrounding and substantially parallel to said first tube, said tubes providing a dome containing trapped gas, said outer tube having an opening therein for admitting oil thereto to provide contact between the trapped gas and the oil, said opening being so positioned that the trapped gas is retained in the dome by the oil, said inner tube having an opening therein at said dome to transfer the pressure of said gas past the oil between said tubes, and a reservoir containing gas under pressure connected to said tubes, said reservoir also containing oil connected to the oil in said cable.

9. A cable comprising a conductor, insulation about the conductor including an oil, a fluid-tight sheath about the insulation, a tube between the conductor and sheath containing gas, a tube containing gas surrounding and substantially parallel to said first tube, said tubes providing domes containing trapped gas, said outer tube having an opening between the domes for admitting oil thereto to provide contact between the trapped

gas and the oil, said openings being so positioned that the trapped gas is retained in the domes by the oil, said inner tube having an opening therein at one of said domes to transfer the pressure of said gas past the oil between said tubes.

10. A cable comprising a conductor, insulation about the conductor including an oil, a fluid-tight sheath about the insulation, a tube between the conductor and sheath containing gas, a tube containing gas surrounding and substantially parallel to said first tube, said tubes providing domes containing trapped gas, said outer tube having an opening between the domes for admitting oil thereto to provide contact between the trapped gas and the oil, said openings being so positioned that the trapped gas is retained in the domes by the oil, said inner tube having an opening therein at one of said domes to transfer the pressure of said gas past the oil between said tubes, and a reservoir containing gas under pressure connected to said tubes.

11. A cable comprising a conductor, insulation about the conductor including an oil, a fluid-tight sheath about the insulation, a tube between the conductor and sheath containing gas, a tube containing gas surrounding and substantially parallel to said first tube, said tubes providing domes containing trapped gas, said outer tube having an opening between the domes for admitting oil thereto to provide contact between the trapped gas and the oil, said openings being so positioned that the trapped gas is retained in the domes by the oil, said inner tube having an opening therein at one of said domes to transfer the pressure of said gas past the oil between said tubes, and a reservoir containing gas under pressure connected to said tubes, said reservoir also containing oil connected to the oil in said cable.

12. A cable comprising a conductor, insulation about the conductor including a liquid, a fluid-

5 tight sheath about the insulation, a tube containing gas disposed within said sheath, said tube having a part thereof elevated above the remainder of said tube, an outer tube originally containing gas surrounding and substantially parallel to the first tube and providing a space therebetween, said outer tube having openings at intervals to provide access between the liquid and the space between tubes, said first mentioned tube having 10 openings at much longer intervals than the outer tube to provide access between the gas in the first tube and the space between tubes.

13. A system of electrical transmission consisting of a plurality of lengths of cable and joints between said lengths, said cable comprising a conductor, insulation about the conductor including a liquid, a fluid-tight sheath about the insulation, a tube containing gas disposed within said sheath, said tube having a part thereof elevated above the remainder of said tube, an outer tube originally containing gas surrounding and substantially parallel to the first tube and providing a space therebetween, said outer tube having 15 openings at intervals to provide access between the liquid and the space between tubes, said first mentioned tube having openings at said joints to provide access between the gas in the first tube and the space between tubes, and a reservoir external to said cable containing gas 20 connected to said first mentioned tube.

14. A cable comprising a conductor, insulation about the conductor including a liquid, a fluid-tight sheath about the insulation, a tube containing gas disposed within said sheath, and an outer tube originally containing gas surrounding and substantially parallel to the first tube and providing a space therebetween, said outer tube having 25 an opening therein for admitting liquid thereto.
